A. B. TURK

PLASTER BOARD

Filed Dec. 20, 1924

INVENTOR.
A. B. TURK,

BY
J. G. Quisada
ATTORNEY.

UNITED STATES PATENT OFFICE.

ALONZO B. TURK, OF OKMULGEE, OKLAHOMA.

PLASTER BOARD.

Application filed December 20, 1924. Serial No. 757,177.

To all whom it may concern:

Be it known that I, ALONZO B. TURK, a citizen of the United States, and a resident of Okmulgee, in the county of Okmulgee and State of Oklahoma, have invented certain new and useful Improvements in Plaster Boards, of which the following is a specification.

This invention relates to building material and more particularly to plaster boards as a ground for the interior and exterior walls.

An object of the invention is the provision of a plaster board having a plurality of co-operative locking devices for maintaining a plaster or stucco finish on the board.

A further object of the invention is the provision of undercut grooves and raised ribs incorporated in a plaster board for respectively locking a surface coating to the board and for forming a directional means for a workman whereby an even surface coating may be applied.

Other objects and advantages will be apparent during the course of the following description.

In the accompanying drawing forming a part of this application and in which like numerals are employed to designate like parts throughout the same,

Figure 1 is a perspective view showing a form of plaster board for exterior finish.

Figure 2 is a perspective view disclosing a modified form for interior walls.

Figure 3 is a detail sectional view illustrating an edge reinforcement for the improved board.

In the drawing the numeral 1 designates the main body of the board, which board is formed of a composition of gypsum and wood fibre or any material found suitable for the purpose. The drawing clearly illustrates that the outer side of the board is formed with a plurality of spaced approximately parallel undercut grooves 3 for the reception of a portion of the final or skim coat designated by the numeral 9. It is thus seen that the final or skim coat 9 is intimately joined with the board 1 to resist cracking or peeling as the result of changes in weather conditions.

Figure 3 plainly illustrates that a coarse layer of burlap 6 is stretched across the outer surface of the board 1 and spans the undercut grooves 3 so that it is necessary for the plaster or stucco 9 to be forced through

the burlap to enter and firmly seat in the grooves 3. By reason of this arrangement the coarse burlap is extended through substantial portions of the coat 9 to assist the undercut grooves in holding the coat firmly in place.

The outer side of the board 1 may be provided at intervals of eight inches, more or less, with approximately parallel raised ribs 4 which act as a furring means and a gauge to assist the plasterer in obtaining a final coating of a uniform thickness. Figure 2 plainly illustrates that the coarse burlap 6 extends about the undercut rib 4 and may be joined in any suitable manner with the undercut side walls of the same.

In case the improved plaster board is used for exterior work as illustrated in Figure 1, the raised ribs 4 will provide a spacing means for an open work metallic reinforcing member 7. After a wall has been formed by the application of a plurality of the improved plaster boards to the studs the open work metallic reinforcing element 7 for the coating of plaster is applied and anchored at suitable intervals to the boards. When the final coat 9 is applied in a plastic state a portion of the same will easily pass through the open reinforcing element 7 and when forced through the burlap 6 will enter the grooves 3 and firmly attach itself to the body 1.

In summarizing it will be seen that there are three separate means to hold the final coat in position. The undercut grooves 3 constitute the first and possibly the major means to hold the final coat in place. The coarse burlap 6 forms the second means for holding the final coat in place while the reinforcing element 7 forms the third means for holding the final coat in place.

Figure 3 illustrates that the edge portions of the boards may be slightly spaced when applied to the studding 25 and the edges of the boards are beveled to provide a groove 100 for the reception of a portion of the plaster. Therefore, when the final coat is applied the plaster which enters the space between the edges of the boards as clearly shown in Figure 3 will form a key by 105 which the final coat is further held in place.

Another important feature of the invention is illustrated in Figure 3 wherein it is shown that the board 1 may be backed with building or other paper 30 of a suitable 110

weight and the paper or backing 30 is extended about the beveled edges of the board as shown in Figure 3. This figure also illustrates that the edge portion of the backing 30 is extended over the outer surface of the board a substantial distance into overlapping relation with the adjacent portion of the coarse burlap. In fact, the edge portion of the coarse burlap is embedded in the plaster forming the body 1 and the plaster which works its way through the edge portion of the burlap will adhere to the inwardly extending edge portion 32 of the backing thereby forming an extremely durable edge for the plaster board.

Having thus described the invention, what is claimed is:

1. A building board for wall construction comprising a composition base having spaced undercut grooves at one surface and a burlap of coarse mesh stretched across the surface and covering the grooves whereby a cementitious coating applied to said surface may be forced through the burlap to fill the grooves.
2. A building board for wall construction comprising a composition base having spaced undercut grooves at one surface and a burlap of coarse mesh stretched across the surface and covering the grooves whereby a cementitious coating applied to said surface must be forced through the burlap to fill the grooves, and ribs on the application surface.
3. A building board for wall construction comprising a composition base having spaced undercut grooves at one surface and a burlap of coarse mesh stretched across the surface and covering the grooves whereby a cementitious coating applied to said surface must be forced through the burlap to fill the grooves, and ribs having undercut sides, the burlap covering said ribs in close contact.
4. A building board for wall construction comprising a composition base having spaced undercut grooves at one surface and a burlap of coarse mesh stretched across the surface and covering the grooves whereby a cementitious coating applied to said surface must be forced through the burlap to fill the grooves, ribs on the application surface, and a coarse mesh wire screen supported in spaced relation with said surface of the board by the ribs.
5. A building board for wall construction comprising a composition base having spaced undercut grooves at one surface and a burlap of coarse mesh stretched across the surface and covering the grooves whereby a cementitious coating applied to said surface must be forced through the burlap to fill the grooves, and a paper cemented to a surface of the board.
6. A wall board comprising a body, bur-

lap applied to the outer side of the body and having its edge portion embedded in the body, and a backing extended about the edge of the body and into overlapping engagement with the edge portion of the burlap.

7. A wall board comprising a body, burlap applied to the outer side of the body and having its edge portion embedded in the body, and a backing extended about the edge of the body and into overlapping engagement with the edge portion of the burlap, a portion of the body being extended through the edge portion of the burlap and united with the adjacent portion of the backing.

8. A wall board comprising a body burlap applied to the outer side of the body and having its edge portion embedded in the body, and a backing extended about the edge of the body and into overlapping engagement with the edge portion of the burlap, a portion of the body being extended through the edge portion of the burlap and united with the adjacent portion of the backing, the edges of the body being beveled.

9. A wall board comprising a body, burlap applied to the outer side of the body and having its edge portion embedded in the body, and a backing extended about the edge of the body and into overlapping engagement with the edge portion of the burlap, a portion of the body being extended through the edge portion of the burlap and united with the adjacent portion of the backing, the outer side of said body being provided with grooves spanned by said burlap.

10. A plaster board comprising a body, a layer of coarse burlap applied to the outer side of the body and having its edge portion embedded in the adjacent portion of the body, and a reinforcing element for the edge of the body extended about the outer surface of the body and into overlapping engagement with said burlap, the material forming said body being forced through the edge portion of said burlap into bonding engagement with the reinforcing element.

11. A plaster board comprising a body having a plurality of undercut grooves and having spaced raised ribs forming a gauge for indicating the proper thickness for a finishing coat, and a reticulated member extending across said grooves and being secured to the sides of said ribs.

12. A plaster board comprising a body having a plurality of undercut grooves and having spaced raised ribs forming a gauge for indicating the proper thickness for a finishing coat, said raised ribs also forming a spacing means to space a reinforcing element from the outer surface of the body.

13. A wall board comprising a body having a plurality of spaced grooves for the

reception of a portion of a cementitious coating, and a loosely woven binding member of fibrous material applied to the outer surface of the body and extending across 5 said grooves, said loosely woven binding member being normally spaced from and free from contact with the bottom walls of said grooves and being penetrated by said coating.

10 14. A building board comprising a body, a plastic holding reticulated member applied

to the outer surface of the board and having its edge portion embedded in the body.

15. A building board comprising a body, a plastic holding reticulated member applied to the outer surface of the board and having its edge portion embedded in the body, and an edge reinforcement for the board having a portion extended inwardly from the edge of the board into overlapping 20 relation with said reticulated member.
